UNITED STATES PATENT OFFICE.

JOSEPH ALENA, OF PERTH AMBOY, NEW JERSEY.

WHEELBARROW TOY.

1,304,141.

Specification of Letters Patent.

Patented May 20, 1919.

Application filed February 14, 1919. Serial No. 276,997.

To all whom it may concern:

Be it known that I, JOSEPH ALENA, a citizen of the United States of America, residing at Perth Amboy, in the county of Middlesex, in the State of New Jersey, have invented certain new and useful Improvements in Wheelbarrow Toys, of which the following is a specification.

The primary object of the invention is the provision of a toy in the form of a wheelbarrow adapted for producing noise, the intensity of which depends upon the rapidity of travel of the wheelbarrow over the ground, provision being made for preventing the noise when desired during the travel of the wheelbarrow.

A further object of the invention is to provide a noise-producing toy having separate means for alternately producing similar sounds, the rapid travel of the vehicle rendering these sounds in a substantially continuous noise.

A still further object of the invention is to provide a noise-producing toy that is easy and inexpensive to manufacture and possesses great strength, the structure consisting of two parts which are not liable to get out of order, ready means being also provided to turn off the noise.

With these general objects in view the invention consists in the combination and arrangement of parts hereinafter fully described in connection with the accompanying drawing and in which like reference characters designate corresponding parts throughout the several views.

Figure 1 is a view of my invention partly in side elevation and partly in vertical longitudinal section,

Fig. 2 is a view similar to Fig. 1, showing the invention in vertical longitudinal section,

Fig. 3 is a top plan view thereof with parts broken away, and

Fig. 4 is a perspective view of the switch employed with the device.

My invention has the appearance of a wheelbarrow in which a wheel 10 is carried by an axle 11 journaled adjacent the forward ends of the side rails 12 of the vehicle, the rear ends of the rails being slightly curved forming handles 13.

A bottom plate 14 is secured beneath the rails 12 while a curved top plate 15 is pro-

vided above said bottom plate. A ratchet 55 wheel 16 is provided upon the axle 11 at each side of the wheel 10, springs 17 being provided, of different lengths normally engaging the teeth of the wheel 16, with the rear ends of the springs 17 secured as at 18 60 to a transverse brace 19 provided between the rails 12 adjacent the handle portions 13 and between the plates 14 and 15.

The springs 17 forwardly project from the brace 19 between the plates 14 and 15 and 65 are tensioned in their engagement with the wheels 16 and by reason of the springs 17 being of different lengths, and the teeth of the wheels 16 being positioned in corresponding planes, the springs 17 will be released at 70 different and alternate times by the teeth of the wheels 16 so as to produce sounds alternately during the forward travel of the wheel 10. Upon moving the wheelbarrow forwardly with great rapidity, the alternate sounds produced by the springs 17 upon the wheel 16 are so close together as to sound substantially continuous and producing a 75 roaring noise.

A T-shaped switch 20 is provided with a 80 cross head 21 slidably mounted in opposite slots 22 in the rails 12 for bracing upwardly beneath the springs 17 for elevating the brace out of engagement with the wheels 16. The switch 20 has a rearwardly projecting handle 23 centrally attached to the cross head 21 and slidably mounted through a slot 24 in the brace 19, a block 25 being provided upon the handle 23 rearwardly of the brace 19 while a pin 26 is carried by the 85 said handle inwardly of the said brace. The block 25 and pin 26 limit the sliding movement of the switch 20 and it will be seen that when the switch 20 is retracted with the springs 17 released, the noise will 90 be produced by the springs striking the successive teeth of the wheel 16 to open forwardly moving the switch 20, by forcing the block 25 forwardly, the springs 17 will be 95 prevented from engaging the wheels 16 and the noise will be interrupted.

A strong toy is provided and one in which articles may be carried by placing the same upon the upper plate 15 which is slidably curved for retaining articles thereon while 100 the approach of the wheelbarrow can be readily noted by means of the sound produced by the wheels 16 and springs 17, al-

though this sound or alarm may be turned off by means of the switch 20 whenever desired.

What I claim as new is:—

- 5 1. A device of the class described comprising side rails, an axle journaled adjacent the forward ends of said rails, a transverse brace between the rails spaced from the rear ends thereof, a ground wheel, upon said 10 axle, sprocket wheels upon the axle at opposite sides of the ground wheel and opposite springs secured at their rear ends to said brace with their forward ends in normal resilient engagement with said sprocket 15 wheels, a bottom plate upon said rails and a curved plate upon the top of the rails adapted for the reception of articles to be carried.
2. A device of the class described comprising side rails, an axle journaled adjacent 20 the forward ends of said rails, a transverse brace between the rails spaced from the rear ends thereof, a ground wheel, upon said axle, sprocket wheels upon the axle at opposite sides of the ground wheel and opposite 25 springs secured at their rear ends to said brace with their forward ends in normal resilient engagement with said sprocket wheels, a bottom plate upon said rails, a curved plate upon the top of the rails adapted 30 for the reception of articles to be carried, the side rails having inclined slots therethrough, a switch having a cross head slidably mounted in said slots and positioned for bearing beneath the said springs where- 35 by the springs are adapted for separation from the sprocket wheels when the switch is forwardly positioned, an arm rearwardly

projecting from said head through said brace and a block upon the free end of said arm rearwardly of the brace.

40

3. A sounding toy comprising in combination with a wheelbarrow having opposite rails and an axle journaled therebetween provided with a ground wheel, the rear end portions of the rails serving as handles for the vehicle, a transverse brace between the rails rearwardly of the ground wheel, upper and lower plates carried by the rails with said brace positioned therebetween, a sprocket wheel carried by the axle at each 50 side of the ground wheel, opposite springs of different length having their rear ends secured within said brace and their forward ends normally engaging the sprocket wheels at relatively different points upon the wheels 55 whereby alternate sounds are produced by the springs upon the sprocket wheels during the forward travel of the ground wheel, the side rails having opposite inclined slots between said plates and the brace having a 60 substantially central opening therethrough, a T-shaped switch having its cross head slidably mounted in said slots and its rearwardly projecting arm extending through said opening, the springs resting upon the 65 switch head whereby the forward movement of the switch is adapted for elevating the springs above the sprocket wheels, a stop pin through the switch arm forwardly of the brace and an engaging block upon the free 70 end of said arm rearwardly of the brace.

In testimony whereof I affix my signature.

JOSEPH ALENA.
